CONTINUOUS COOKER-COOLER DRIVE

Eli Bourland, Millbrae Highlands, Calif., assignor
to Pacific Can Company, San Francisco, Calif.,
a corporation of Nevada

Application June 4, 1945, Serial No. 597,544

4 Claims. (Cl. 99—365)

1

This invention relates to improvements in can-handling machinery, and in particular is directed to improvements in can-handling machines in which the can is propelled endwise by a track in an elongated pocket while its contents are being treated.

For a long time the industry has struggled with the problem of eliminating wear on the end flange of sealed cans produced by the track as it pushes the can along the pocket in the propelling reel. Various solutions have been suggested, such as the employment of rollers to form the elongated pocket so that the can will be kept rolling while it is being pushed endwise by the track. Another suggestion for solving the problem has been the use of the lead and no-lead track, as first shown in the patent to Chapman, No. 1,646,577.

The object of the present invention is to solve this problem by providing a novel form of track member which has the effect of reducing the friction between the track and the end of each can. Tests have shown that the drag and wear on the can is substantially eliminated.

This has a decidedly advantageous effect on the operation of the whole machine, for, because with the drag of the prior art track on the cans, more horsepower has been needed to rotate the propelling reel, and also it has been impossible to run the machines at as high a speed as would otherwise be possible because of the damage to the ends of the cans which seemed to increase as the speed increased. The result of the invention therefore is that less power is needed in operating the machine, and it can be operated at higher speeds than has heretofore been possible without injury to the can ends.

In compliance with U. S. Rev. Stat. Sec. 4888, an illustrative embodiment of the invention is shown in the drawings. It is not the intention to limit this patent to the specific form of track shown, as that is purely illustrative of the invention as defined in the claims.

In the drawings,

Fig. 1 is a view in side elevation of what is known in the trade as a continuous cooker or cooler. Some parts are shown broken away, and others are shown in cross section;

Fig. 2 is a view in perspective taken adjacent the right-hand end of the upper broken-away view in Fig. 1;

Fig. 3 is a view in perspective similar to Fig. 2 with the parts rotated about 90° to the right; and

Fig. 4 is a plan view of a portion of the type of track and reel showing the relationship of the can to the track and the reel.

2

The invention is to be described in connection with a can track apparatus of the horizontal drum type employing a horizontally mounted rotatable reel having elongated pockets for conveying the cans in a generally helical path through the drum, and a track member therein surrounding the reel pockets and having a radial member adapted to advance each can axially in its respective pocket. This form of machine is illustrated in the Smith Patent No. 628,554. It comprises the drum 10, set on a horizontal axis, and having mounted on the shaft 11 a reel 12 made up of angle irons 13 set so as to provide elongated pockets or troughs 14 along which the cans 15 may slide endwise. As shown in the middle broken-away view of Fig. 1, these angle irons or pocket members 13 are inclined slightly to the axis of the reel 12. This is also illustrated in Fig. 4.

Secured around the inside of the drum 10 is a track 16, usually made of metal bars in the form of a T having the flat portions 17 and the radial member 18. This track may have what is known in the industry as a constant lead or constant helix, as shown in the Smith patent, or it may have a lead and no-lead helix, as shown in the Chapman patent. As used in this description the words "generally helical" are intended to mean any form of track in which the general effect is to propel or guide the cans 15 from one end of the drum 10 to the other end. The cans enter the drum 10 through an inlet valve 19 and exit from the drum through the outlet valve 20. The operation of these valves is well known to those skilled in this art and plays no part in the present invention.

Referring now to Fig. 4, which illustrates a track 16 having a constant pitch to form a helix, it is preferable to have the angular set on the angle irons 13 arranged so that the track 16 and the angle irons 13 cross at substantially a right angle. This means that each can 15 carried by the reel will engage the radial member 18 at two points 21 and 22 on its double seamed end. This two-point contact is not absolutely essential and does not exist in all positions in the case of the lead and no-lead spiral track 16.

As shown in Fig. 4 the end of the can opposite the points 21 and 22 is not in contact with the radial member 18 of the next turn of track. The reason for this is that it is the radial member 18 on the other end of the can which is propelling the can endwise in the reel pocket 14 in the direction of the arrow. The clearance space 23 is desirable because at times there is some variation in

the length of cans, and also for one reason or another they may bulge on the ends during certain types of treatment.

On the impelling or working side 24 of the radial member 18 of the track 16 is provided a bead 25 which may be of a half round, quarter round, bulb-nosed, chamfered, or oval shape in cross section. Its shape will be that which will give the least friction between it and the two points 21 and 22 where it contacts the end of the can. This bead or side bearing member preferably is made of a non-corrodible low-friction type of material and extends axially outwardly from the working side 24 of the radial member 18 so that it is offset axially with relation to the surface 24. This means that whenever the can 15 is being pushed axially endwise along the reel trough 14, the bead 25 is the only part of the track member 16 in contact with the can end.

It is customary for machines of this type to have the drum 10 filled either with steam or water or other material which causes the reel and the track parts to rust and corrode very quickly. Also, during the off seasons, when the equipment is lying idle in the canneries, this rusting process continues unabated. The bead 25 may be secured to the radial member 18 by means of rivets 26 or it may be formed as an integral part of the radial member 18, in which case all or part of the radial member preferably would be made of a non-corrodible material, or at least be sheathed with it.

There are many different ways of obtaining an axially offset edge 25 for the radial member 18, and it is not my intention to limit the invention to any particular form for this bearing surface or member 25. In the claims where reference is made to the bead and the side bearing member being the only part of the track member in contact with the can while guiding it in its pocket, this is not to be taken to mean that when in the lower half of its cycle the can does not also roll on the surface 17 of the track 16. What the claim language is intended to mean is that the bead or side bearing member 25 is the only part of the radial portion of the track in contact with the end of the can.

What is claimed is:

1. In a can-treating apparatus of the horizontal drum type employing a horizontally mounted rotatable reel having elongated pockets for conveying the cans in a generally helical path through said drum, and a track member therein surrounding said reel pockets and having a radial member adapted to advance each can axially in its respective pocket, said radial member having formed thereon a bead or rib-like antifriction bearing member extending axially outwardly from the wall of said radial member and from end to end of said member, whereby said bead

is the only part of said track member in contact with a can end while guiding it in its pocket.

2. In a can-treating apparatus of the horizontal drum type employing a horizontally mounted rotatable reel having elongated pockets for conveying the cans in a generally helical path through said drum, and a track member therein surrounding said reel pockets and having a radial member adapted to advance each can axially in its respective pocket, said radial member having secured thereon a smooth low-friction non-corrodible side bearing member in position to engage the end of each can whenever advancing it in its pocket, whereby said side bearing member is the only part of said track member in contact with a can end while guiding it in its pocket.

3. In a can-treating apparatus of the horizontal drum type employing a horizontally mounted rotatable reel having elongated pockets for conveying the cans in a generally helical path through said drum, and a track member therein surrounding said reel pockets and having a radial member adapted to advance each can axially in its respective pocket, said radial member having formed thereon a continuous bead extending axially outwardly from the wall of said radial member, whereby said bead is the only part of said track member in contact with a can end while guiding it in its pocket.

4. In a can-treating apparatus of the horizontal drum type employing a horizontally mounted rotatable reel having elongated pockets for conveying the cans in a generally helical path through said drum, and a track member therein surrounding said reel pockets and having a radial member adapted to advance each can axially in its respective pocket, said radial member having formed thereon a non-corrodible bead or rib extending axially outwardly from the wall of said radial member, whereby said bead is the only part of said track member in contact with a can end while guiding it in its pocket.
